METHOD AND APPARATUS FOR PRODUCING
SPECIAL ELECTRIC FIELDS

Bindo Riccioni, Rome, Italy

Application February 15, 1935, Serial No. 6,740
In Italy November 24, 1934

6 Claims. (Cl. 250—1)

The present invention relates to a method and to the corresponding apparatus for producing very steep variations in electromagnetic and electrostatic fields and its object is to increase the exciting voltage on bodies, even those of small dimensions, and more particularly upon objects used in connection with biological and physico-chemical tests.

The device may include several systems of multiple circuits with condensers and impedances in series. The apparatus is substantially formed of a simple or primary circuit provided with spark gaps in which the discharge is started at predetermined intervals. The said primary circuit excites one or more circuits (secondary, tertiary etc.) formed in the same way, that is with capacities and impedances in series, the values of which may be equal to or different from those of the capacities and impedances of the primary circuit.

The device is not adapted to produce current for distribution. It is used for producing electric and electrostatic fields having a very steep gradient in a very small space into which certain objects may be placed for biological and other experiments, such as seeds or cells. These objects are placed in the spark gap of the innermost circuit.

The discharge circuit according to the invention is fed from the secondary circuit of a step up transformer of the tension, the primary circuit of which is provided with low tension alternating current.

The starting of the discharge within the aforesaid spark gaps of the primary circuit may be effected in two ways; that is, with spontaneous excitation by giving the current, which feeds the primary circuit, an appropriate and sufficient voltage to overcome the said intervals (feeding with variable voltage), or by causing the excitation to take place by means of switches which close the circuit at a predetermined moment (feeding with variable voltage and with constant voltage).

Electromagnetic and electrostatic fields having a very steep gradient, that is of the order of thousandths of a microsecond between the maximum values and the minimum values, are produced between the terminals of the last induced circuit, which consists of a simple condenser formed of armatures of suitable shape facing one another. In all cases the spark gap between the said extremities of the last circuit must have well defined values in respect of the

characteristics of the stresses to be imparted upon the subjects.

In all induced elementary circuits the impedance is formed by the discharge itself, and in many cases the last circuit of the system is formed of two insulated spheres. In all, at least in all double systems, the increase of the voltage which excites the system is produced in the secondary circuit.

In all the systems of circuits, of which the apparatus according to the invention is composed, the unavoidable resistance in series with the impedance and the capacity must have the least possible value, and in any case its maximum value should not exceed a few ohms, for the purpose of obtaining sharp variations of the electromagnetic field. If, on the contrary, high resistances are added having the value of several megohms, shunted upon the extremities of the various coupled circuits, these resistances have the effect of producing abrupt variations of the electrostatic field.

The apparatus according to the present invention will be described hereinafter with reference to the accompanying diagrammatical drawings illustrating by way of example several embodiments of the apparatus with various systems of electric circuits. In these drawings

Fig. 1 shows a double circuit system for the production of impulse discharges.

Figs. 2 and 3 show two different systems of multiple circuits, with four and three induced circuits respectively, and which are also designed for the production of impulse discharges.

Figs. 4 and 5 show two different systems of circuits with variable voltage and provided with a switch having a predetermined constant speed, or with a synchronous switch if alternating current is employed.

Figs. 6 and 7 show triple and quadruple circuits, respectively, fed with variable voltage, and provided with a switch, as stated above.

Figs. 8 and 9 are two double and quadruple circuits, respectively, fed with continuous high voltage current.

Figs. 10, 11, 12 and 13 show double, triple and quadruple circuits, respectively, fed with variable voltage and comprising a high resistance, and

Fig. 14 shows a quadruple circuit provided with a high resistance and fed with continuous high voltage.

In Fig. 1 *b.t* denotes the alternating low voltage current which feeds the primary circuit; *T* is the transformer with high resistance and capacity uniformly distributed on the impedance,

for the generation of high voltage current from the primary circuit; P—P represents the whole of the induced circuits according to the invention, in which C is the capacity, L the impedance, 5 r the resistance, $C_1—C_2$ are two capacities in the primary circuit, different from each other, the difference of which may in certain cases sink down to 5%; $l_1—l_2$ are concentrated impedances inserted in the main circuit, $r_1—r_2$ being distributed resistances having a very low value (less than one tenth of an ohm), such resistances being due to the natural resistance of the conducting wires.

M, N are the extremities of the outer or primary circuit; H, K are the extremities of the inner or secondary circuit. There is a gap between the poles M and N in which the electric discharge takes place, thus influencing the poles H and K of the secondary circuit. The spark 10 gap between the poles H and K of the secondary circuit is quite independent of the outer or primary circuit and becomes connected with it only when an electric discharge takes place between the poles M and N of the outer circuit. The 15 intervals for the discharges of connection and insertion of the secondary circuit on the primary circuit are represented by D, d; their sparking over causes in a the discharge having the desired characteristics; e represents the connection to the ground. In the described scheme the centre 20 of the transformer generating the high voltage currents is connected to earth.

The system illustrated in Fig. 1 comprises two 25 circuits, namely, an external circuit which includes the two outer balls M and N of the spark gap, and an intermediate circuit which comprises balls H, a, located within the spark gap of the external circuit. No induction exists between the external circuit and the intermediate 30 circuit. The same is also true as far as the systems illustrated in other figures of the drawings are concerned, where there is also no induction between the various intermediate circuits.

In the circuit system shown in Fig. 2, the 35 terminals of the intermediate circuits S_2 and S_3 as well as those of the central inner circuit S_4 are inserted between the terminals of M_1 and N_1 of the outer circuit S_1 . The gap of the circuit S_4 is the centre of discharge of all the circuits. 40 As shown in the drawings these various circuits are arranged alternately on opposite sides of the spark gaps from which it will be apparent that there is no inductive action between the various intermediate circuits. The ground connection is 45 represented by the reference character e.

Fig. 3 shows another circuit system according to the invention, also fed with alternating low voltage current, which is produced by the transformer T. This transformer has the same 50 characteristics as the transformers disclosed above with reference to Figs. 1 and 2. The system illustrated in Fig. 3 contains only two induced circuits, that is the secondary circuit S_2 and the tertiary circuit S_3 . All the other reference characters like those indicated in the two 55 preceding figures denote corresponding elements of the circuits described.

In Fig. 1 the secondary circuit, and in Figs. 2 and 3 the secondary circuit, the tertiary circuit 60 etc. are the elementary circuits, which in some examples may be formed only with two balls, which form the armatures of the condenser, while the discharge forms the impedance and the 65 resistance of the circuit.

In the circuits shown by way of example in Figs. 4, 5, 6 and 7 the sparking over of the discharge in the spark gaps is obtained by causing the excitation to take place by means of a rotary switch I_s (shown for simplicity's sake only in Fig. 4) having a predetermined constant speed, thus permitting to feed the circuit either with alternating current or with a current having a constant voltage. The rotary switch I_s shown in Fig. 4 is supplied with an alternating current and comprises upper and lower spark gaps S_1 which become active at the peak of each wave of the alternating current. The angular speed of the rotary switch is synchronized with the wave period of the A. C. to attain this result. 15 When a direct current is used, as shown, for example, in Figs. 8 and 9, the rotary switch I_s is provided at its periphery with a number of radial projections which pass close to the balls forming the spark gaps in the feeding circuit and thereby 20 cause the actuation of these spark gaps.

In Fig. 4 γ and β are the two points at which the primary high voltage circuit should be interrupted, and the reference character bt indicates a source of alternating current. T is a step-up 25 transformer, C_1 is the capacity and I' and r' are, respectively, the inductance and the resistance of the circuit, S_2 indicating the ends of interruption of the external or primary circuit. The arrows indicate the direction of the rotation. 30

Figs. 5, 6 and 7 show induced double, triple and quadruple circuits obtained in the manner described with reference to Figs. 1, 2 and 3, that portion of them, which lies before the points x and y , being omitted.

Figs. 8 and 9 show two further examples of 35 circuits for obtaining electric fields having very steep variations, by applying to the primary circuit a continuous high voltage current. In these circuits γ and β are the points in which the said high voltage current is applied; I_s are two rotary switches having a constant speed, like those already described, inserted in series in the circuit, Fig. 8 representing a double circuit and Fig. 9 a quadruple circuit, that is provided with 40 three induced circuits in the way described above.

Fig. 10 shows the example of a simple device, the primary of which is fed with alternating high tension current. It is provided with a rotary switch I_s , like that described with reference to Fig. 4, and with a resistance R of several megohms shunted upon the primary circuit.

Figs. 11, 12 and 13 show partially examples of 45 circuits similar to those of Fig. 10, (in which the portion situated before x and y has been omitted) capable of working with variable high voltage current. They comprise a resistance R of several megohms which is shunted on the primary circuit; the reference characters indicating the other elements of the circuit being the same as 50 those denoting corresponding parts in the other circuits.

Fig. 11 shows a double circuit, Fig. 12 a triple circuit and Fig. 13 a quadruple circuit, which correspond to the circuits shown in Figs. 5, 6 and 7, 55 respectively.

It will be observed that also in Figs. 3, 13 and 14 the intermediate circuits have been arranged alternately on opposite sides of the spark gap to indicate that there is no inductive action between 60 the intermediate circuits.

Lastly Fig. 14 shows partially another example of a quadruple circuit, capable of being fed with continuous high tension current, and which differs from that shown in Fig. 9 only because of 65

a resistance R of several megohms being inserted in it.

In all the systems of circuits described above a considerable increase of the tension, as compared with the one which excites the system, is obtained at the final discharge. 5

The apparatus according to the invention may be used in connection with biological tests to vary the electromagnetic and the electrostatic field 10 inside the living cells so as to affect the characteristics of their development. In physico-chemical experiments it may be used for the purpose of varying also the electric charges of the molecule and of the atom.

15 I claim:

1. A system for producing electric and magnetic fields which rapidly vary in value and direction for the treatment of small objects, said system comprising a number of oscillating circuits which have no inductive effect one upon the other, a feed circuit, each of said oscillating circuits having a spark gap, the spark gaps of the oscillating circuits being arranged in series, said oscillating circuits comprising an outer circuit 20 having a spark gap which encloses the spark gaps of all other circuits, any other spark gap of an oscillating circuit being situated within another spark gap constituting a part of another oscillating circuit, and means interposed between said feed circuit and said outer oscillating circuit for transmitting electrical energy from said feed 25

circuit to said outer oscillating circuit to produce a discharge at desired intervals at the spark gap of the outer circuit, whereby the discharge at the spark gap of the outer circuit interconnects all other oscillating circuits, the object to be treated 5 being introduced into the innermost spark gap.

2. A system according to claim 1, in which means for producing the periodical discharges transmit a periodically variable current whereby the voltage periodically reaches such values as 10 are sufficient to secure the sparking through the air gaps provided in the outer oscillating circuit.

3. A system according to claim 1, in which the periodical discharges are obtained by means of a rotary switch having a constant speed of rotation, whereby the circuit through which flows the current is closed at the predetermined 15 moment.

4. A system according to claim 1, in which a high resistance, of several megohms, is shunted 20 upon the ends of one of said oscillating circuits.

5. A system according to claim 1, comprising a step-up transformer in said outer oscillating circuit, the middle points of its windings being 25 grounded.

6. A system according to claim 1, comprising a step-up transformer in said outer oscillating circuit, in which the feeding winding is sub-divided into successive equal portions shunted between the line wires. 30
